UNITED STATES PATENT OFFICE.

DALVIN C. HIBBARD, OF SEATTLE, WASHINGTON.

FIRE-ESCAPE.

1,123,295.

Specification of Letters Patent.

Patented Jan. 5, 1915.

Application filed March 12, 1914. Serial No. 824,201.

To all whom it may concern:

Be it known that I, DALVIN C. HIBBARD, a citizen of the United States, residing at Seattle, in the county of King and State of Washington, have invented certain new and useful Improvements in Fire-Escapes; and I do hereby declare the following to be a full, clear, and exact description of the invention, such as will enable others skilled in the art to which it appertains to make and use the same.

My invention relates to new and useful improvements in fire escapes and resides in the provision of a flexible ladder that may be quickly and easily let down from the window of a building and as easily wound upon a drum, forming a part of the invention, when not in use.

An important object of my invention is to provide a fire escape of the character described which comprises a flexible ladder that is constructed in a novel form so that strength, durability and extreme lightness is provided thus enabling women and children or weak persons to operate the escape so as to have expeditious escape from a burning building.

An important object of my invention is to provide a novel form of rung construction for the ladder forming a part of my invention which enables the provision of a light ladder and one that may be readily wound upon a winding drum in such a way that entanglement of the ladder is prevented and ready letting down of the ladder from a window is permitted.

Another important object of my invention is to provide a fire escape of the character described which is simple as to construction, reliable and efficient in operation, capable of being readily installed in buildings and houses and which is cheap to manufacture.

The above and additional objects are accomplished by such means as are illustrated in the accompanying drawings, described in the following specification and then more particularly pointed out as claimed.

With reference to the drawings, wherein I have illustrated the preferred embodiment of my invention as it is reduced to practice, and throughout the several views of which similar reference numerals designate corresponding parts; Figure 1 is a vertical sectional view of a building showing my improved fire escape attached and in operative

position, also one side of the winding drum broken away to show a portion of the flexible ladder wound up on the drum, Fig. 2 is a front elevation of my improved fire escape, 60 Fig. 3 is a fragmentary side elevation of the ladder showing the construction and arrangement of the rungs, Fig. 4 is a detail top plan view of one of the rungs and connecting plates, Fig. 5 is a cross sectional 65 view taken through the central portion of one of the rungs and coöperating parts showing a portion of the flexible elements connected therewith, and Fig. 6 is a detail 70 view of a modified form of rung construction wherein the elements are separate as opposed to the integral as shown in the preferred form.

Referring to the drawings by characters of reference A represents the wall of a 75 building provided with a window B and floor C.

A winding drum designated 1 as an entirety having its shaft 2 mounted in two pair of upright bearing standards 3 is disposed upon the floor C adjacent to the window B. Suitable fastening means 4 inserted through angular lugs or flanges 5 on the lower end of the standard 3 serves to secure the standard to the floor C. One end of the 85 shaft 2 is squared to receive a crank handle 6.

A ladder designated 7 as an entirety and of the flexible type is secured at one end in any suitable manner to the drum 1 and arranged to be wound thereon. The sides of the ladder 7 consist of a plurality of flexible elements designated 8 and 9 and which in this instance are illustrated as chains.

Connecting the ends of the flexible elements or chains are rectangular connecting plates 10 formed of any suitable material and provided adjacent each end with openings 11 to receive the end links 12 of the chains 8 and 9. The connecting plates 10 are flat and disposed to lie in the same plane as the flexible elements 8 and 9 when the ladder 7 is in its extended position.

Rungs 13 are connected with the plates 10 and disposed in spaced relation thereto 105 in a plane approximately at right angles to the plane of the flexible elements and plates. The rungs 13 comprise rods or bars of some suitably light metal that have their ends bent to provide right angular extensions 14, 110 said extensions being preferably formed integral with the plates 10 at points approxi-

mately centrally of the longitudinal edges of the plates 10 and adjacent to the end edges thereof. It will be readily seen that the rungs 13 extend outwardly at right angles to the plates 10 and flexible elements 8 and 9, thus enabling persons in descending from a burning building to have a secure and readily accessible footing with relation to the rungs. The positioning of the rungs 13 also enables the spacing of the flexible elements when the ladder is wound upon the drum 1 as clearly shown in Fig. 1. This arrangement prevents entanglement and insures an expeditious unwinding of the ladder 7.

It will be readily seen with reference to the foregoing description and accompanying drawings that I have provided a simple and inexpensive fire escape which is strong and durable and yet extremely light. In case of fire the persons seeking escape from the building simply have to place the free end of the ladder out of the window B and allow the same to unwind from the drum or if necessary pull the ladder from the drum and allow it to drop to the ground.

With particular reference to Fig. 6 wherein I have shown a modified form of rung construction, the numeral 15 designates a connecting plate similar to the ones 10. Secured to the plate 15 is a rung 16 similar to the ones 13 but having its ends enlarged at points slightly spaced from the ends and then reduced to provide extensions 17 which are inserted through openings in the plate 15 and mashed to act as rivets. Plates 18 having apertures adjacent the ends thereof are secured transversely of the plates 15 adjacent the ends thereof by the extensions 17, said extensions extending through a central aperture in the plates 18. The end openings in the plates 18 receive the end links of the chains after the same manner as employed in the preferred form. This modified form enables ready assembling and disassembling of the ladder and in some instances may prove more desirable than the integral construction embodied in the preferred form.

In practice, I have found that the form of my invention, illustrated in the drawings and referred to in the above description, as the preferred embodiment, is the most efficient and practical; yet realizing that the conditions concurrent with the adoption of

my device will necessarily vary, I desire to emphasize the fact that various minor changes in details of construction, proportion and arrangement of parts may be resorted to, when required, without sacrificing any of the advantages of my invention, as set forth.

What is claimed is:—

1. A fire escape comprising a flexible ladder, said ladder comprising a plurality of 65 flexible side elements, transverse connecting plates loosely connected with the ends of said side flexible elements and disposed in a similar plane to said flexible elements and rungs carried by said connecting plates, 70 said rungs comprising bars having said portions disposed in spaced parallel relation to said connecting plates and having right angularly disposed ends extending at right angles to the vertical plane of said 75 connecting plates.

2. A fire escape comprising a ladder consisting of a plurality of flexible side elements, flat transversely arranged connecting plates loosely connected with the ends 80 of said side elements and arranged in spaced relation to each other, said plates having openings at each end to receive the ends of said flexible elements, rungs secured to said plates and having mid portions disposed in spaced parallel relation thereto, said rungs having right angularly bent terminals extending at right angles to the plane of said plates and operatively connected therewith at points approximately centrally of the 85 longitudinal edges of the plates adjacent the end edges thereof.

3. A fire escape comprising a ladder consisting of flexible side elements, plates arranged transversely of said side elements 90 and loosely secured to the ends thereof, transverse plates mounted adjacent the ends of said connecting plates, said plates having alining openings to receive the ends of said flexible elements and rungs having mid 100 portions arranged in spaced relation to said connecting plates and having right angularly bent terminals extending through said plates and secured to said connecting plates.

In testimony whereof I affix my signature in presence of two witnesses.

DALVIN C. HIBBARD.
